DES. 1930

Daniel Moore, of Brooklyn, New York.
Letters Patent No. 1930 Dated April 5th 1864.
Design for a Revolving Pistol Handle.

The schedule referred to in these Letters Patent and making part of the same.

To all whom it may concern:

Be it known that I, Daniel Moore, of the City of Brooklyn, in the County of Kings and State of New York, have invented a new Design for a Revolving Pistol Handle, and I do hereby declare that the following is a full, clear and exact description of the same, reference being had to the accompanying drawings forming a part of this specification, in which -

Fig. 1. is a side view.

Fig. 2. is a back view.

Fig. 3. is a top view.

Similar letters of reference indicate corresponding parts in the several figs.

In its side profile, the top, back and lower part of the handle present substantially the form of a spiral curve as shown at a, b, c, d, in fig. 1, the curvature gradually increasing from the upper part around to and under the bottom where it meets the

DES. 1930

3

hollow curve c, of the side profile of the front lower part of the handle, and forms therewith an angle f. The butt c, and bottom d, are of nearly semispheroidal form. The sides of the handle commencing at the recoil shield R, are nearly straight in their horizontal profile which is shown in fig. 2, with a gradual swell in a rearward direction, but toward the butt have a slight hollow curvature as shown at i, so that they form a sharp or nearly sharp line or edge g, at their junction with the semispheroidal surface of the butt and bottom, as shown at figs. 1 and 2, the said line g, forming a continuation of the angle f, before mentioned with reference to fig. 1, and extending obliquely and with a slight curvature across the sides of the handle.

The top and back a and b, and the front lower part d, of the handle have a rounded transverse section.

What I claim as my invention, and desire to secure by Letters Patent is

The design and configuration of the revolving, pistol handle herein described and represented in the accompanying drawings.
